PANEL FOR THE INTERIORS OF AIRCRAFT

Harold E. Johnson, 8335 Groveland Road,
Minneapolis 32, Minn.

Filed Jan. 9, 1963, Ser. No. 73,120

Term of patent 14 years

(Cl. D71—1)

The figure is a front elevational view of a panel for the interiors of aircraft showing my new design.

The panel is of no appreciable thickness and is slightly embossed on the front and is continued around the slight wall projection shown.

The portions shown in broken lines are included for illustrative purposes only.

I claim:

The ornamental design for a panel for the interiors of aircraft, as shown and described.
